UNITED STATES PATENT OFFICE.

HERMAN PRIES, OF MICHIGAN CITY, INDIANA.

CAR-BOLSTER.

No. 914,073.

Specification of Letters Patent. Patented March 2, 1908.

Application filed August 3, 1908. Serial No. 446,610.

To all whom it may concern:

Be it known that I, HERMAN PRIES, a citizen of the United States, residing at Michigan City, in the county of Laporte and State of Indiana, have invented certain new and useful Improvements in Car-Bolsters, of which the following is a specification, and which are illustrated in the accompanying drawings, forming a part thereof.

10 The invention relates to bolsters for cars, and is applicable either to body bolsters or to truck bolsters.

15 The object of the invention is to secure great strength in a bolster of comparative lightness and simplicity of construction, and it consists in a structure hereinafter described, and which is illustrated in the accompanying drawings, in which,—

20 Figure 1 is a longitudinal view of a pair of body and truck bolsters, partly in elevation and partly in vertical section; Fig. 2 is a bottom plan view of the body bolster, partly in section; Fig. 3 is a detail plan view of the truck bolster; and Fig. 4 is an end view of the body bolster.

25 The two bolsters are substantially alike, the essential difference being of design rather than structure.

Referring particularly to the body bolster, 30 it comprises a pair of channel bars 10, 11 arranged with their web portions vertical and spaced apart, and their flanges directed outwardly or away from each other. To the lower flanges of these channel bars there is 35 applied and securely riveted a bottom plate 12, the length of which is the same as the length of the bolster, and its side edges being preferably flush with the outer edges of the lower flanges of the channel bars. To the 40 upper flanges of the channel bars there is applied and securely riveted a top plate 13, the length of which is the same as the length of the bolster, its width, however, being such that its side edges extend beyond the edges 45 of the upper flanges of the channel bars.

In order to lessen the vertical dimension of the bolster adjacent its ends, both for the purpose of affording ample clearance for other parts of the car and lessening the 50 weight at the parts where the minimum load is carried, the lower portions of the channel bars 10 and 11 are chamfered obliquely upwardly toward their ends through approximately one third of their length. This chamfering removes so much of the lower flange of

the channel bar, and its place is supplied by an angle bar 14, one leaf of which is applied to the inner face of the web of the channel, to which it is securely riveted, its other leaf bearing against the inclined edge of the chamfered portion of the channel bar and projecting outwardly. At the inner end of the angle bar, its outwardly projecting flange abuts against the end of the lower flange of the channel bar, as shown at 15.

60 The bottom and top plates 12 and 13 are centrally pierced to receive the king bolt 16, and a socket block for affording ample bearing for this bolt is located within the bolster. The body of this block is shown at 17. 70 To this body portion are integrally connected a pair of plates 18, 19, which bear against the inner faces of the web portions of the channel bars 10 and 11, to which they are securely riveted. The usual center plate 20 is 75 secured to the lower face of the body bolster, and co-operates with the usual center plate 21 applied to the upper face of the truck bolster. The usual side-bearing plates 22, 23 are secured to the lower face of the body bolster adjacent its ends, and co-operate with bearing blocks 24, 25 secured to the upper face of the truck bolster. The truck bolster has channel bars 26, 27, a bottom plate 28, and a top plate 29, which are substantially 80 the same as the corresponding parts of the body bolster. Preferably, the top plate is of less width than the top plate of the body bolster, and its side edges may be flush with the edges of the upper flanges of the channel bars. 85 A bearing block 30 for the king bolt is incorporated within the truck bolster, and is the same in form as the block 17 in the body bolster. In order to afford proper clearance 90 for the other portions of the truck, not shown, the lower portions of the outer ends of the truck bolster are offset upwardly, these offset portions being connected with the central section of the bolster by inclined portions 31, 32. To supply the place of the portions of 95 the lower flanges of the channel bars which are removed in thus reducing the vertical dimension of the bolster at its ends, angle bars 33 are secured to the channel bars, the same as in the case of the body bolster, except, of course, that the angle bars are bent to conform to the shape of the truck bolster.

100 While there are shown a pair of bolsters, one for the body of the car, and the other for the truck, which are of substantially identical 110

construction, they are not necessarily associated in pairs, as either may be used with another bolster of different construction.

Having thus described my invention, I
5 claim:

In a bolster in combination, side members
of channel bars having their flanges out-
wardly directed, the lower faces of such bars
being chamfered adjacent their outer ends,
10 angle bars secured to the channel bars at

their chamfered portions, one leaf of each
angle bar forming a continuation of the
flange of the side member, top and bottom
plates riveted to the flanges of the side mem-
bers, and a king-pin bearing to lock secured 15
within the body of the bolster.

HERMAN PRIES.
